US0D1068030S

(12) **United States Design Patent** (10) **Patent No.:** **US D1,068,030 S**
(45) **Date of Patent:** **** Mar. 25, 2025**

(54) **HOSE END SPRAYER**

(71) Applicant: **Silgan Dispensing Systems Corporation**, Grandview, MO (US)

(72) Inventor: **Brandon L. Ramsuer**, Henrico, VA (US)

(73) Assignee: **Silgan Dispensing Systems Corporation**, Grandview, MO (US)

(**) Term: **15 Years**

(21) Appl. No.: **29/843,249**

(22) Filed: **Jun. 20, 2022**

Related U.S. Application Data

(62) Division of application No. 29/818,148, filed on Dec. 7, 2021, now Pat. No. Des. 958,936, which is a division of application No. 29/697,504, filed on Jul. 9, 2019, now Pat. No. Des. 940,272, which is a division of application No. 29/630,861, filed on Dec. 22, 2017, now Pat. No. Des. 859,584.

(57) **CLAIM**

The ornamental design for a hose end sprayer as shown and described.

DESCRIPTION

FIG. 1 is a perspective view of a hose end sprayer in accordance with the present design;

FIG. 2 is a rear view thereof;

FIG. 3 is a front view thereof;

FIG. 4 is a left side view thereof;

FIG. 5 is a right side view thereof;

FIG. 6 is a top view thereof; and,

FIG. 7 is a bottom view thereof.

The elements shown in broken lines in the Figures form no part of the claimed design.

1 Claim, 7 Drawing Sheets
